Primary Examiner — Philip S Hyder(74) *Attorney, Agent, or Firm* — John E Boyd; FisherBroyles, LLP(57) **CLAIM**

The ornamental design for a dispenser cartridge, as shown and described.

DESCRIPTION

FIG. 1 is a rear perspective view of a dispenser cartridge, showing the new design;

FIG. 2 is a left-side view thereof;

FIG. 3 is a right-side view thereof;

FIG. 4 is a front view thereof;

FIG. 5 is a rear view thereof;

FIG. 6 is a top view thereof; and,

FIG. 7 is a bottom view thereof.

The broken lines in the drawings depict environmental subject matter only and form no part of the claimed design.

1 Claim, 4 Drawing Sheets(56)
